UNITED STATES PATENT OFFICE

EPHRAIM K. SPYKER, OF SACRAMENTO, CALIFORNIA

PLOW PLANE

Application filed August 27, 1929. Serial No. 388,790.

This invention relates to certain new and useful improvements in plow planes, such as are used by carpenters and cabinet makers for cutting different kinds of grooves, fil-
5 listering, dadoing, or rabbeting and the primary object of the invention is to provide a plane stock wherein different sizes of chisels
5 listing, dadoing, or rabbeting and the primary object of the invention is to provide a plane stock wherein different sizes of chisels
5 may be used.

A further object of the invention is to
10 provide a plow plane of the above type with a guide frame adjustable thereon to be moved along the edge of the work for guiding the plane in its cutting or shaving operation, together with a depth gage for regulating the
15 depth of cut of the plane.

A still further object of the invention is to provide a plow plane of the above type that is capable of cross-grain work by the provision of scribing points at the forward
20 end of the plow frame separated a distance equal to the width of the cutting end of the chisel or bit to permit an even cross-grain cut or shave and eliminating the possibility of a ragged edge at opposite sides of the chisel
25 or bit.

With the above and other objects in view that will become apparent as the nature of the invention is better understood, the same consists in the novel form, combination and
30 arrangement of parts hereinafter more fully described, shown in the accompanying drawings and claimed.

In the drawings:—

Figure 1 is a side elevational view of a plow plane constructed in accordance with the present invention;

Figure 2 is a top plan view of the same;

Figure 3 is a vertical longitudinal sectional view taken on line 3—3 of Figure 2, showing the forwardly positioned scribe for cross-grain cutting with a chisel mounted in the frame of the plane together with the depth gage plate adjustable on the frame of the plane;

Figure 4 is a vertical longitudinal sectional view taken on line 4—4 of Figure 2;

Figure 5 is a bottom plan view of the plane with parts removed and showing the guide frame in extended positions; and also illustrated by dotted lines in folded positions.

Figure 6 is a perspective view of the chisel or bit rest removed from the plane frame;

Figure 7 is a front elevational view of the plane;

Figure 8 is a perspective view of the depth gage plate removed from the plane; and

Figure 9 is a perspective view of the forward end plate of the frame of the plane.

The plow plane stock or frame comprises a bottom plate or wall 11 carrying vertical side walls 12 formed intermediate their ends with substantially triangular-shaped portions 13 of increased height and shorter rear portions 14, the forward ends of the side wall portions 12 being connected by a forward vertical cross-wall 15 set inwardly of the terminal ends of said portions 12 and having a lower cross foot portion 16 flush with the wall 11 of the plane. A vertical cross wall 17 is disposed between the terminal forward ends of the side walls 12 and is anchored in position by the screws 18 passing through openings 18a shown in Figures 3 and 9 with a vertical channel or space remaining between the cross walls 15 and 17. The opposed faces of the cross walls 15 and 17 are vertically corrugated or grooved as at 19 for the selective reception of cutting blades 20 spaced apart a distance substantially equal to the width of the chisel or bit of the plane for scribing lines on cross grain work so that the chisel or bit will cut a groove and leave a clean straight edge, which operation will be later described in detail. The handle carried by the rear end of the bottom plate or wall 11 shown in Figure 3 comprises a socket member 21 rising from the bottom wall 11 for receiving the tenon 22 on the handle portion 23 to be retained therein by the cross screw 24.

A chisel or bit rest is mounted upon the bottom wall 11 shown in Figures 3 and 4 and comprises, as shown in detail in Figure 6, a vertical rear wall 25 and a forwardly inclined wall 26, the two walls being slotted as at 27 with a part of the vertical rear wall cut away as at 28 providing a clearance for other structures, the rest being retained in position upon the bottom wall 11 by the attaching screw 29 shown in Figure 4 passing

through the apertured lug 30 on the vertical rear wall 25 of the rest and engaging the up-struck abutment 31 upon the bottom wall 11, the rest being positioned between the side wall portions 13 of the plane with the forward inclined wall 26 positioned rearwardly of the cross wall 32 connecting the forward portions of the side wall sections 13, and providing a space for the mounting of a chisel or bit.

10 A depth gage is associated with the plane and as shown in Figures 3 and 8 comprises an elongated gage plate 33 attached to the frame of the plane and extending downwardly through the longitudinal slot 34 formed in the bottom wall 11. The forward end of the gage plate 33 is inclined as at 35 at the same angle as the forward wall 26 of the chisel or bit rest and has a cooperating gage foot 36 disposed at the same angle as the inclined end 35 with the lower edge thereof in the same plane as the lower edge of the gage plate 33 and connected thereto by the laterally offset arm 37. A binding screw 41 passes through an inclined slot 42 in the side wall 12 of the plane as shown in Figures 3 and 4 and enters the aperture 40a in the arm 37 to aid in holding the gage plate in position. An angle lug 43 carried by a centrally raised portion of the gage plate 33 has a screw 44 swiveled therein that threads into block 45 carried by the base plate 11 the knurled finger piece 44a being provided for adjusting the gage plate relative to the bottom wall of the plane. Upon loosening the screw 41, the gage plate 33 and gage foot 36 are adjusted by the screw 44 to vary the depending projection of the lower edge of the gage plate and foot relative to the bottom face of the wall 11, the screw 41 moving through the slot 42 and when the proper adjustment has been accomplished, the screw 41 is tightened and the gage plate and gage foot held rigidly positioned, the binding screw 52 threaded 45 inwardly through the wall 14 holding the rear end of the gage plate 33 in position. A cutting device such as a bit or chisel 45a is mounted with the bit end thereof upon the forward wall 26 of the rest and rearwardly of the foot 36. A filler bar 47a is inserted in chosen ones of the registering grooves 26a formed in the opposed faces over substantially one half the width of the rest wall 26 and cross bar 32 providing an abutment for one 50 side of the chisel while the other side thereof is engaged by the screw 47 threaded through the adjacent side wall 13 of the frame, the forward side of the chisel being further anchored by the screw 48 threaded through the cross wall 32. A spring plate 49 is anchored as at 50 at the upper end of the cross wall 32 with the lower angle end 49a directed toward and engaging the chisel blade to cause the shavings to rise upwardly 55 through the plane frame and to be removed

from the rear of the throat through which the bit or chisel blade extends, the tension of the spring plate 49 being controlled by a knurled nut 51 threaded upon the screw 48 and engaging the spring plate shown in Figure 3. The bit or chisel is thereby rigidly supported as is also the gage plate 33, an added locking feature for the gage plate including the screw bolt 52 threaded through a side wall portion 14 of the plane frame 75 into end contact with the gage plate as shown in Figures 2 and 3.

A guide frame is associated with the plane and comprises side bars 53 and 54 having hinged extensions 55 connected thereto as at 56, with the side bar 53 and its hinged extension 55 passing through openings in the side walls 12 at the front end of the plane and retained in adjusted position by the screw 57 threaded through the lug 58 at the upper end 80 of the front cross wall 15, while the other side bar 54 and its hinged extension 55 passes through a cross opening in the socket section 21 of the handle and is retained in adjusted position by the screw stud 58a. The 90 ends of the side bar extensions 55 are cut away as at 59 upon opposite sides to cause the ends to overlap when moved upon their hinged connections 56 as shown in Figure 7, when the guide frame is folded adjacent the 95 plane. If desired, additional extensions 55a may be attached to the free ends of the side bar extensions 55. The outer ends of the side bars 53 and 54 are connected by a cross bar 60 provided with a hand grip 61 intermediate its ends while a depending angle arm 62 is formed at each end of the cross bar 60 to which a guide bar 63 is hingedly attached to be moved into engagement with the edge of the work being grooved. The side 100 bar 63 moves into engagement with the straight edge of the work with the plane resting thereon, the plane being adjustable to position the bit or chisel 45a at the proper point for forming the desired groove or the 105 like and the parts are so retained by the tightening screws 57 and 58a for the guide frame. The gage plate 33 is adjustable as 110 previously described for determining the depth of cut and in doing cross-grain work, the scribes 20 are lowered below the bottom wall 11 of the plane to form side cuts at opposite sides of the bit or chisel.

From the above detailed description of the invention, it is believed that the construction 115 and operation thereof will at once be apparent, and while there is herein shown and described the preferred embodiment of the invention, it is nevertheless to be understood that minor changes may be made therein 120 without departing from the spirit and scope of the invention as claimed.

I claim:

1. In a plane of the character described, a frame; a tool rest of inverted substantially 130

V-form mounted on the frame and having slots in the spaced side walls thereof and said frame being longitudinally slotted in alinement with the rest slots, and a depth gage comprising a blade extending through the rest slots and depending through the frame slot.

2. In a plane of the character described, a frame, a tool rest of inverted substantially V-form mounted on the frame and having slots in the spaced side walls thereof and said frame being longitudinally slotted in alinement with the rest slots, a depth gage comprising a blade extending through the rest slots and depending through the frame slot, and an inclined slot and pin connection between the forward end of the gage blade and frame.

3. In a plane of the character described, a frame, a tool rest of inverted substantially V-form mounted on the frame and having slots in the spaced side walls thereof and said frame being longitudinally slotted in alinement with the rest slots, a depth gage comprising a blade extending through the rest slots and depending through the frame slot, an inclined slot and pin connection between the forward end of the gage blade and frame, and an adjusting screw associated with the frame and gage blade for raising and lowering the blade.

4. In a plane of the character described, a frame, a tool rest of inverted substantially V-form mounted on the frame and having slots in the spaced side walls thereof and said frame being longitudinally slotted in alinement with the rest slots, a depth gage comprising a blade extending through the rest slots and depending through the frame slot, an inclined slot and pin connection between the forward end of the gage blade and frame, an angle lug carried by the gage blade, a screw swivelled in the angle lug and a block on the frame into which the screw is threaded for raising and lowering the gage blade.

In testimony whereof I affix my signature.
EPHRAIM K. SPYKER.
